BEADED ARTIFICIAL TREE OR THE LIKE

Margaret R. Wender, 4201 Cathedral Ave. NW.,
Washington, D.C. 20016

Filed Feb. 24, 1967, Ser. No. 5,944

Term of patent 14 years

(Cl. D29—1)

FIGURE 1 is a side elevational view of a beaded artificial tree embodying my new design.

FIGURE 2 is a bottom plan view thereof, the broken line illustration of the base being omitted for convenience of illustration; and

FIGURE 3 is an enlarged, detailed plan view of one of the branches and leaves of the tree.

The essential features of my design reside in the portions shown in solid lines; a conventional base being shown in broken lines in FIGURE 1.

I claim:

The ornamental design for a beaded artificial tree or the like, as shown and described.
